UNITED STATES PATENT OFFICE.

LE ROY W. FAIRCHILD, OF NEW YORK, N. Y.

DESIGN FOR PENCIL-CASES.

Specification forming part of Design No. 11,414, dated September 16, 1879; application filed August 7, 1879.
[Term of patent 7 years.]

To all whom it may concern:

Be it known that I, LE ROY W. FAIRCHILD, of the city, county, and State of New York, have produced a new and original Design for an Ornamental Pencil-Case, or chain-amulet carrying a pencil or other small implement, of which the following is a full, clear, and exact description, reference being had to the accompanying engraved illustration, making part of this specification.

The invention consists in ornamenting the said case with a Maltese cross having in its center a small working-compass, and having also the surfaces of the four radiating sections of the cross ornamented with figures in bas-relief.

A is a representation of the complete design. b is the stem-ring. c c are the ends of the case proper. d d d d are the four radiating sections of the cross, which are to be ornamented with figures in bas-relief after selected designs significant of social emblems or otherwise. e is the central compass.

What I claim as my invention is—

A design for a small implement case, consisting of the tube or case ring and Maltese cross, the latter having a working-compass in the center, and having also its four radiating sections ornamented with figures in bas-relief, substantially as hereinbefore described.

LE ROY W. FAIRCHILD.
